SAFETY LINE ROPE GRAB

Walter H. Huntley, 4650 Centre Road N., and Charles W. Huntley, 4644 Centre Road N., both of Cooksville, Ontario, Canada

Filed Aug. 27, 1962, Ser. No. 71,451

Term of patent 14 years

(Cl. D54—11)

FIGURE 1 is a perspective view taken from the top and one side of a safety line rope grab showing our new design.

FIGURE 2 is a view similar to FIGURE 1 showing the side opposite to that shown in FIGURE 1.

FIGURE 3 is a side elevation with the larger ring in elevation.

FIGURE 4 is a front elevation from the side of the device on which the larger ring is disposed.

FIGURE 5 is a plan view.

FIGURE 6 is a cross sectional view on the line 6—6 of FIGURE 3, with the end portion omitted for convenience of illustration only.

We claim:
The ornamental design for a safety line rope grab, as shown and described.
